RETAINING WALL CONSTRUCTION

Sylvain Louis Ravier, Paris, France

Application December 12, 1928, Serial No. 325,567
In France December 15, 1927

7 Claims. (Cl. 61—39)

This invention relates to the construction of retaining walls formed from either precast blocks or masonry or formed in certain cases in situ of concrete or reinforced concrete.

5 A main object of the invention is to reduce the cost of forming a wall without however diminishing the strength, stability and other desirable properties thereof.

10 The invention comprises the formation of a wall which is substantially hollow and whose cross section is such that a relatively small cross section is secured at the bottom of the wall while a far larger cross section is obtained at the top of the wall.

15 An essential feature of the invention is to so construct the wall that the slope of the filling located in back of the wall approaches as near as possible within reason the natural slope of the filling under the effect of gravity by providing 20 upon said wall retaining surfaces or back curtains of adequate configuration as to diminish the thrust of the filling upon said wall.

25 Also in the further carrying out of this particular feature, whenever the maximum thickness of the wall may become unreasonably great, the invention contemplates permitting the thrust to exert itself against the back curtain only upon part of the height of the wall and allowing the filling to attain its natural slope inside a portion 30 of the wall. This is accomplished by eliminating portions of the back curtain along the height of the wall thereby nullifying the thrust of the filling at such eliminated portions.

35 A further object of the invention is to provide supporting ribs and a ceiling in order to provide an approach from the back of the wall to a position substantially vertical above the foot of the front side of the wall, and also to control the amount of the filling, if any, which may be permitted inside of the wall.

40 It is the purpose of the invention through the furnishing of ribs and a ceiling in order to provide empty recesses in the wall in order to secure a wall of minimum weight and to combine this advantage 45 of minimum weight with the advantage of minimum thrust afforded by the back curtains which control the thrust.

45 It is a still further object of the invention to combine the reduced weight and thrust and arrange the elements of the invention in such a manner as to obtain a resultant force which will pass through substantially the middle third of the base of the wall.

50 With these and other objects in view which will become apparent from the detailed description of the invention set forth below, the invention comprises the combination and arrangement of elements set forth below claimed in the claims and shown in the drawings, in which

55 60 Figure 1 is a vertical sectional view taken on

the section line 1—1 of Figure 4 looking in the direction of the arrows.

5 Figure 2 is a vertical sectional view taken along the section line 2—2 of Figure 4 looking in the direction of the arrows.

Figure 3 is a similar cross sectional view taken along the section line 3—3 of Figure 4 and looking in the direction of the arrows.

10 Figure 4 is a cross sectional view extending longitudinally along a composite wall formed of various constructional blocks and elements taken along a section 4—4 of Fig. 1 and looking in the direction of the arrows.

15 Figure 5 is a front elevational view of the composite wall shown in Figure 4.

Figure 6 is a horizontal sectional view along the section line 6—6 of Figure 4.

20 Figure 7 is a horizontal sectional view taken along the section line 7—7 of Figure 4 and looking in the direction of the arrows.

25 Figure 8 is a view taken on the section line 8—8 of Figure 13.

30 Figure 9 is a similar view taken on the section line 9—9 of Figure 13 looking in the direction of the arrows.

35 Figure 10 is a sectional view taken on the section line 10—10 of Figure 13 looking in the direction of the arrows.

40 Figure 11 is a sectional view taken on the section line 11—11 of Figure 13 looking in the direction of the arrows.

45 Figure 12 is a vertical cross sectional view taken on the section line 12—12 of Figure 13 and looking in the direction of the arrows.

50 Figure 13 is a sectional view of another form of composite wall extending longitudinally along the length of said wall in a vertical plane, and

55 Figure 14 is a horizontal cross sectional view of the composite wall shown in Figure 13 taken along the section line 14—14 of Figure 13.

60 In the drawings, particularly Figures 4 and 13, there is illustrated a wall formed of composite elements. It is to be understood however, that these elements in certain walls may be made alike throughout the length of the wall or various combinations of the same may be used to satisfy certain local conditions.

65 Referring particularly to Figure 1 and Figure 4, there is disclosed a concrete hollow retaining wall formed by piling hollow concrete blocks upon one another. The vertical pillars 101 and 102 are formed by superposing blocks 11, 12, and 13 which have a central vertical rib 16 with back curtains 25 as shown more particularly in Figure 6.

70 By the construction indicated, the entire block 55 has a T section as clearly shown in Figures 6 and 7 and the blocks are of trapezoidal shape, increasing in size as shown in Figure 1, so as to form a rear wall 15—15 inclined against the filling so as to reduce the thrust of the filling.

In Figure 2 a modification of the pillar is shown forming the vertical pillar 104 as illustrated in Figures 4 to 7 inclusive. In this case each block is provided with front curtains 26 corresponding 5 to the rear curtains 25 so that a juxtaposition of the blocks will form a continuous vertical wall at the front similar to the inclined wall at the rear.

In order to prevent the pressure of the blocks 10 upon the sub-structure or ground upon which they are disposed from becoming too great, and especially if such sub-structure should consist of rather poor soil, there is provided a bed of rubble or sand 17 and in addition there is provided at 15 the bottom of the lower blocks 11 wings or extensions 18 which are generally of sufficient size so as to contact adjacent wings or extensions 18 and thereby form a continuous base for the pillars as shown particularly in Figures 4 and 5.

20 In some cases it is advantageous to further increase the base by forming upon the lower blocks enlargements or extensions 19 at the front, thereof, as shown in Figures 1 and 2 and in some cases wherever desired, similar projections or extensions 25 20 may be provided at the rear as shown in Figure 2.

The upper blocks 13 are surmounted at the rear by a ceiling which in the section of wall shown in Figure 1 is formed by extensions or 30 wings 21 integral with the central vertical rib 16. In the form of the invention shown in Figure 2 however, in order to increase the stability of the pillar of blocks under construction they are surmounted by blocks or slabs of concrete or reinforced concrete 21^a forming the ceiling which are arranged upon the vertical ribs 16 which are recessed for this purpose.

Another modification of the invention is shown with relation to pillars 103 and 104 as illustrated 40 in Figure 4 in which the slabs constituting the ceiling are made in the form of small arches 21^b.

At the front of the wall a coping 14 is arranged. This may be formed in situ upon the blocks 13 and may be a solid integral piece such as shown 45 in Figure 1 or it may be of lighter construction as shown in Figure 2.

The blocks 11, 12, and 13 shown in Figure 1 and which form the pillars 101 and 102 and also 50 103, have small lateral auxiliary bracing lugs or spacing elements 23 serving to space the blocks constituting each pillar with respect to the adjacent pillars against buckling. Upon the pillar 103 these spacing elements 23 are as shown particularly in Figure 5, made somewhat shorter in order 55 to bear against the front curtains provided at the front of the blocks constituting the pillar 104.

In some cases the spacing elements 23 may be constituted by merely disposing the ends of 60 wooden rods in the concrete or masonry. These rods of wood may in some cases be disposed out of line with the front of the wall.

In accordance with the section of wall shown in Figure 2 and the wall portions 106 and 106^a as shown in Figures 4 to 7 inclusive, each block 65 is provided with three ribs 16^a, 16^b and 16^c, thereby forming two internal recesses 27 and 28, which recesses similar to the recesses formed with the single vertical rib are to remain empty in order to keep the total weight of the wall as light as 70 possible.

In the form of invention illustrated by the wall portions 106 and 106^a, the purpose is to render 75 the blocks more stable and also to permit an alternation of the horizontal course of successive

blocks as shown clearly in Figure 4. In this case the wall may be constructed as is done with ordinary blocks and the central rib of one block may support the end ribs of two blocks superposed thereon while the adjacent end ribs of the superposed two blocks will in turn support the central rib of the block superposed thereupon. It is obvious that in some cases blocks having more than two internal recesses may be used.

A further modification of the wall is shown in 10 Figure 3 and also illustrated by the pillar 105 shown in Figures 4 to 7 inclusive.

In this case the rear part of the wall is composed of blocks which are arranged vertically similar to the front part, but the thrust against 15 the rear wall formed is reduced in the following manner. In the first place in this construction a slab 21^b is laid as a ceiling upon the upper block in cantilever fashion extending towards the rear, which will provide a sloping of the filling 29 in the manner shown in Figure 3, thereby eliminating the thrust of the filling upon the rear of the upper blocks for a certain distance. This result is increased by eliminating the rear covering of the lower block so that an opening 30 will 25 be provided by means of which an incline 31 of the filling is produced at the bottom part of the wall, thereby reducing the thrust thereagainst. In all the other modifications relating to the invention the interior of the wall is designed to be 30 empty, but in this modification the interior of the wall is allowed to be slightly filled with the filling so as to reduce the thrust against the wall.

An important feature of the present invention resides in the fact that the curtains 25 and 26 as well as the extensions 18 and 21 are given sufficient thickness so that they will only become slightly fatigued whereby these elements of the blocks may be made of ordinary non-reinforced concrete or even of masonry. It is for this reason 40 also that these elements are made trapezoidal in shape having a greater thickness at the base thereof.

A further modification of the present invention occurs in connection with retaining walls 45 of terrestrial supports such as along railroad cuts for instance, where the embodiments discussed above are used without any sub-division into blocks and the wall is formed in a single piece throughout from either concrete, reinforced concrete or masonry. Obviously, in such case the spacing elements 23 as shown in Figure 1 and the pillars 101 to 103 will be omitted and the arrangement of the pillars 104 and 106 corresponding to Figure 2 will be the same, in the 55 form of solid vertical ribs, with or without front curtains 26.

It is obvious that the embodiments disclosed above are susceptible of various modifications without departing from the spirit or principle of the invention. Furthermore, the arrangement shown in Figure 1 and in Figure 2 may be used for certain portions in the wall and that of Figure 3 for the remaining portion thereof. Furthermore, the slab 21 shown in Figures 1 and 2 as well as in 60 Figure 3, may be prolonged to the rear and the back curtains connecting the ribs 16 may be dispensed with. It is also obvious that the front of the wall may also be inclined and that the coping wall 14 may in certain other cases be made 65 to project and the under facing thereof may be made concave.

A further modification of the invention consists in reinforcing the lips of the course of the blocks and the topping surface of the upper 75

blocks by giving to these blocks the form of a trapezoid section as shown in Figure 8 and as illustrated at A—A of Figure 13.

In accordance with a still further modification 5 instead of providing a slope such as disclosed in connection with Figures 1 to 7 at the front and rear of the lower blocks, the wall may be made substantially vertical over a small portion adjacent the base at the rear surface of the blocks 10 as shown particularly in Figures 8, 10, and 12 at 1 and 2.

A still further modification is the provision of the rear face of the wall in the form of a series of steps as shown particularly in Figure 9.

15 An arrangement may be used in which the volume of the lower blocks is increased slightly but which are thereby simplified. These blocks at the lower part may be constructed without recesses as shown in Figures 10 and 13 and indicated at B—B of Figure 14. In some instances 20 the upper blocks may be treated in the same manner or there may be provided the same arrangement for other courses of blocks such as one out of every two, for example.

25 In some cases the foundation upon which the lower blocks are laid is formed by means of poured concrete beneath the water instead of rough masonry or sand. The concrete is preferably poured in a dredged channel beneath the 30 level specified for the bottom in front of the quay, as shown in Figures 8, 9, 10, 11, and 12. According to a further variation advantage may be taken of the course of the concrete when poured under water in order to eliminate the enlargement 35 or extension provided at the base of the lower block as shown in Figure 11 and the portion C—C of Figure 13.

In order to facilitate the carrying of the blocks without danger of rupture they may be reinforced 40 with steel bars or wood bars which may be completed by nailing to their ends cross pieces or planks constituting reinforcing frames about the concrete.

45 A further slight change consists in arrangement provided for retaining walls which have been formed by pouring concrete underneath the water. In this case the wall such as shown in Figure 12 and illustrated at the parts D—D—D in Figures 13 and 14, may be formed by pouring 50 concrete into suitable molds and securing the recesses by means of cores. The slab cover constituting the ceiling for the upper blocks may be made in the form of a series of slabs or reinforced concrete made in situ or prepared elsewhere and 55 the cores removed.

The above disclosure illustrates the manner which I at present consider the preferred form of carrying out the invention, but it is to be understood that all forms of the invention as come 60 within the spirit of the following claims are to be included since it is obvious that various modifications may be made therein.

Having described my invention what I claim as new and desire to secure by Letters Patent 65 is:—

1. A concrete hollow retaining wall executed by piling hollow concrete blocks comprising vertical ribs disposed perpendicularly to the front of said wall, a ceiling on said ribs, and back curtains between said ribs on the upper part only of the height, the ceiling and back curtains being

disposed to prevent the filling from falling between the upper parts of the ribs, and a natural slope of said filling between the ribs at the base of the wall.

2. A concrete hollow retaining wall executed 5 by piling concrete blocks of I horizontal sections comprising vertical ribs disposed perpendicularly to the front of said wall, a ceiling and a front coping wall on said ribs and back curtains between said ribs on the upper part only of the 10 height, the ceiling and back curtains being disposed to prevent the filling from falling between the upper parts of the ribs, and a natural slope of said filling between the ribs at the base of the wall. 15

3. A concrete hollow retaining wall executed by piling concrete blocks of T and I horizontal sections comprising vertical ribs disposed perpendicularly to the front of said wall, a ceiling and a front coping wall on said ribs and back curtains between said ribs on the upper part only 20 of the height, the ceiling and back curtains being disposed to prevent the filling from falling between the upper parts of the ribs, and a natural slope of said filling between the ribs at the base 25 of the wall.

4. A concrete hollow retaining wall, executed by piling hollow concrete blocks, comprising vertical ribs disposed perpendicularly to the front of said wall, a ceiling and a front coping wall on 30 said ribs, and back curtains between said ribs, the ceiling and back curtains being disposed to prevent the filling retained by the wall from falling between the ribs of the wall and an extension of said ceiling back of the ribs, and a 35 natural slope of said filling under said extension of the ceiling.

5. A concrete hollow retaining wall executed by piling concrete blocks comprising vertical ribs disposed perpendicularly to the front of said wall, 40 a ceiling resting upon said ribs and projecting to the rear of said wall so that the filling may assume a natural slope below said projecting end of said ceiling, back curtains between said ribs on the upper part only of the height of the wall 45 and the lower part having an opening towards the rear so that the filling may assume a natural slope between said ribs at the lower portion of said wall.

6. A concrete hollow retaining wall executed 50 by piling concrete blocks comprising vertical ribs disposed perpendicularly to the front of said wall, a ceiling resting upon said ribs, back curtains between said ribs on the upper part only of the height of the wall and the lower blocks having 55 an opening towards the rear so that the filling may assume a natural slope between said ribs at the lower portion of said wall.

7. A concrete hollow retaining wall comprising 60 vertical ribs disposed perpendicularly to the front of said wall, a ceiling resting upon said ribs and projecting to the rear of said wall so that the filling may assume a natural slope below said projecting end of said ceiling, back curtains between said ribs and the upper part only of the 65 height of the wall and the lower part having an opening towards the rear so that the filling may assume a natural slope between said ribs at the lower portion of said wall.

SYLVAIN LOUIS RAVIER. 70
